UNITED STATES PATENT OFFICE.

JOHN E. CONLEY, OF MEMPHIS, TENNESSEE.

SPRING FROG.

Application filed December 21, 1921. Serial No. 526,151.

To all whom it may concern:

Be it known that I, JOHN E. CONLEY, a citizen of the United States, residing at Memphis, in the county of Shelby and State 5 of Tennessee, have invented a certain new and useful Improvement in Spring Frogs, of which the following is a specification.

This invention relates to spring frogs for railways, and has for its object to provide 10 a new and improved device of this description. The invention has among other objects to provide a frog wherein there is a support for substantially the entire tread of the wheels as they go through the frog, the 15 wheels running on the main or through track as the wheels go through the frog, a portion of the frog being moved by the wheels as they go into the side or less used track, and automatically returning to its initial position. The invention has other objects which 20 are more specifically pointed out in the following description.

Referring now to the drawings—

Fig. 1 is a plan view showing one form of 25 device embodying the invention;

Fig. 2 is a sectional view taken on line 2—2 of Fig. 1.

Fig. 3 is a sectional view taken on line 3—3 of Fig. 1;

Fig. 4 is a view showing a modified construction;

Fig. 5 is a view showing a further modified construction;

Like numerals refer to like parts throughout the several figures.

Referring to the drawings I have illustrated in Fig. 1 one type of frog embodying the invention. It is of course evident that other types than this may be used. In 40 the construction shown the frog 1 is provided with a spring rail 2, movably connected with the frog at 3. This spring rail is provided with an inclined or beveled part 4 at one end. The spring rail when in its 45 normal position fills the space at the side of the frog point in which the flange of the wheel travels. When this space is left open a large part of the tread of the wheel is left unsupported. By means of this spring rail 50 substantially all of the tread of the wheel 5 is supported as shown in Fig. 2 when the wheel is passing through the frog on the main line. When the wheel is passing through the frog to the switch or less used 55 line, the flange is on the other side of the frog point 6 as shown in Fig. 3 and engages the

beveled portion 4 so as to move the spring rail 2 aside into the space 7 as shown in Fig. 3. This spring rail is provided with some means for automatically returning it to its 60 normal position. As herein shown this is done by means of a retracting spring 8, the spring rail being connected therewith in any desired manner so that the retracting spring returns it to its normal position after the 65 wheel passes out of engagement therewith. In the construction shown the spring rail is provided with a projection 9 which engages a part 10 attached to the spring 8. This part 10 is shown as a bolt which passes through 70 the spring. The spring engages the fixed face 11 so that when the spring rail is moved to one side, the spring is compressed, and when the pressure of the wheel is released the spring automatically returns the spring rail 75 to its initial position.

In Fig. 2 I have shown a construction where the frog is of an integral construction.

In Fig. 4 I have shown the frog where it is in sections 12 and 13, which are held together by the fastening devices or bolts 14. It is of course evident that the frog may be made up in any desired manner.

In Fig. 5 I have shown a construction where there are two spring rails 2 and 2^a. 85 These rails fill the space on both sides of the frog point 6 so that substantially all of the tread of the wheel will be supported both when the wheels are passing along the main track, or to the side or less used track. These 90 spring rails are similar to the ones shown in Figs. 1 and 2.

I claim:

1. A frog comprising a frog point, guides to properly direct the wheels when passing through said frog, a rail normally in the space at one side of the frog point and adapted to engage the periphery of the wheel when the flange thereof is on one side of the frog point, said movable rail adapted 100 to be moved to one side by the flange of the wheel when it is on the other side of the frog point.

2. A frog comprising a frog point, a rail normally in the space at one side of the frog point and adapted to engage the periphery of the wheel when the flange thereof is on one side of the frog point, said movable rail adapted to be moved to one side by the flange of the wheel when it is on the other 110 side of the frog point, and means for returning said movable rail to its initial posi-

tion when the pressure of the wheel has been released therefrom.

3. A frog comprising a frog point, a rail movably connected with the frog and located in the space at one side of the frog point and adapted to engage the tread of the wheel when the flange of the wheel is on one side of said frog point, said rail engaged by the flange of the wheel when the flange is on the other side of the frog point so as to move it to one side to permit a free passage of said flange.

4. A frog comprising a frog point, a rail movably connected with the frog and located in the space at one side of the frog point and adapted to engage the periphery of the wheel when the flange of the wheel is on one side of said frog point, said rail engaged by the flange of the wheel when the flange is on the other side of the frog point so as to move it to one side to permit a free passage of said flange, and a retracting device connected to said rail to move it back to its initial position.

5. A frog comprising a frog point, a rail movably connected with said frog point and

located in the space at one side thereof and adapted to engage the periphery of the wheel when the flange of the wheel is on one side of said frog point, said rail having a beveled end which is engaged by the flange of the wheel when it is on the other side of the frog point, said flange moving the rail to one side to permit the free passage of the flange, and a retracting spring connected with said movable rail for moving it back to its initial position when the pressure of the flange is removed therefrom.

6. A frog comprising wheel receiving parts, a spring rail movably connected with said frog and adapted to engage the tread of the wheel when it is passing through the frog one way and adapted to be moved aside by the flange of the wheel when it is passing through the frog in another way, said frog provided with a receiving space into which said spring rail is received when moved aside by the flange of the wheel.

Signed at Chicago, county of Cook and State of Illinois, this 14th day of December, 1921.

JOHN E. CONLEY.
